HATCH COVER WITH HAND HOLD FOR TOP OF RAILWAY GRAIN CAR

William L. Hall, Box 353, Maplewood Ave.,
Lucasville, Ohio 45648

Filed Oct. 26, 1973, Ser. No. 410,285

Term of patent 14 years

Int. Cl. D12—03

U.S. Cl. D12—43

FIG. 1

FIG. 2

FIG. 3

FIG. 4

FIG. 5

FIG. 6

FIG. 1 is a bottom plan view of a hatch cover with hand hold for top railway grain car showing my new design;

FIG. 2 is a top plan view thereof;

FIG. 3 is a side elevational view thereof;

FIG. 4 is a side elevational view thereof opposite to that shown in FIG. 3;

FIG. 5 is an end elevational view thereof; and

FIG. 6 is an end elevational view thereof opposite to that shown in FIG. 5.

I claim:

The ornamental design for a hatch cover with hand hold for top of railway grain car, substantially as shown.
